UNITED STATES PATENT OFFICE.

WILLIAM A. KOCH, OF EVANSVILLE, INDIANA.

CORNER FASTENING FOR BEDSTEADS.

Application filed August 22, 1921. Serial No. 494,342.

To all whom it may concern:

Be it known that I, WILLIAM A. KOCH, a citizen of the United States, residing at Evansville, in the county of Vanderburgh and State of Indiana, have invented certain new and useful Improvements in Corner Fastenings for Bedsteads, of which the following is a full, clear, and exact specification.

10 My invention relates to bedsteads and has reference more particularly to corner fastenings for metal beds using the ordinary angle side rails whereby the side rails may be reversed and adapted to support either the ordinary box spring bottoms, or slats.

15 An object of the invention is to provide a corner fastening that shall be simple in construction, positive in action, and which may be used with any form of bed posts whether of metal or wood.

20 Another object of the invention is to provide a corner fastening for beds which while forming an efficient coupling for the side rails and corner posts will also securely lock 25 the coupling against lateral twisting or turning of the side rails.

With the above and other objects in view my invention consists in certain novel features of construction and arrangement of 30 parts as will be hereinafter fully described and pointed out in the claim, reference being had to the accompanying drawing forming a part hereof, in which:

35 Figure 1 is a perspective view showing my improved corner fastening as in use in one arrangement of parts,

Figure 2 is a similar view showing the reverse arrangement of the parts,

Figure 3 is a transverse section taken as 40 on line 3—3 of Figure 1,

Figure 4 is a vertical section of the arrangement as shown in Fig. 1.

Figure 5 is a perspective view of the headed member of the fastening which is 45 carried by a side rail,

Figure 6 is a perspective view of a socket member which is carried by the corner posts of the bed.

50 Referring more specifically to the drawing it will be noted that the reference numeral 10 denotes the corner post of a metal bed, the post being indicated as of rounding formation by dotted lines.

55 At the most convenient location on the post, which may of course be polygonal or have flat faces, the member 11 of the fasten-

ing is secured by suitable means, this member being a casting; this casting comprises a bracket hollowed out at the rear to form a chamber 12 and having the wings 13 at opposite ends, and the lateral wing 14, said wings provided with openings 15 by which the wings and hence the bracket may be bolted or riveted to the corner post.

Through the front face of the bracket an 65 opening 16 is made, the general shape of this opening being polygonal.

A narrow slot 17 is cut through the front face of the bracket and extends downwardly a suitable distance below the opening 16 with 70 which it merges. By cutting this slot through the face of the bracket spaced apart flanges or ribs 18 are formed and the rear face of these flanges or ribs is slightly rounded or tapered to form wedge or cam 75 faces.

The front face of this member 11 is flat and smooth and is bordered at each side by the vertical flanges 19—19 extending from the upper to the lower end of the face, the 80 inner or opposing faces of these flanges being slightly tapered or converging from the outer edges to the face as indicated by the reference character 20, as will be plainly seen by reference to Figure 3 in the drawing. 85 This disposition of the side flanges results in forming virtually a wide groove in the bearing face of the bracket member.

The other member of the fastening, the 90 fastening as a unit consisting of two members, is to be secured to the side rail 21 or cast integral with it, and consists of a stud 22 projecting from a vertical bearing face 23 of the member, the stud being provided with a head 24 which extends laterally at 95 each side of the stem of the stud.

This stud is preferably cast integral with the vertical web 25 which connects the upper and lower portion of the member, said web 25 being cast integral with said upper 100 and lower portions and extending upwardly some distance on the back face of the member to brace and strengthen same, as shown at 26.

The studded member is also provided 105 with the vertical web 27 and the horizontal web 28 respectively which are riveted to the corresponding flanges of the angle side rail. At the edge opposite the vertical web 27 the member is provided with an integral vertical flange 29 which is cast integral with 110 the body portion and the horizontal web.

28, serving to balance the parts and brace the member at that side.

The sides of the studded member are beveled as shown at 30, or converge, the 5 bevel being complementary and corresponding to that of the flanges 19 on the socket member.

The transversely narrow stem of the stud has as before stated the large head 24 the 10 inner faces of which at opposite sides of the stem has the central bearing surface 24^a and tapered oppositely or curved end portions 24^b. Thus the head will have its greatest diameter in the plane of the bearing 15 surfaces and taper equally in both directions therefrom, so that no matter which end of the head enters the opening 16 and narrow slot 17 of the other or socket member the central bearing surfaces will come in contact with the rear cammed or wedge faces 20 of the ribs 18 and cause the two members to be drawn tightly together when the studded member is forced downwardly.

By this arrangement and disposition of 25 the bearing surfaces of the two members, the reversal of the angled side rails is provided for so that either the ordinary box spring bottom may be used or slats, as desired.

It should be particularly noted that side 30 flanges 19 of the socket member define a wide groove in the face of the member and as the width of the bearing face of the stud as the width of the bearing face of the

studded member is such that it readily slides within said groove, that rocking wabbling 35 or turning of the side rails will be prevented when the members are coupled together.

Furthermore as the groove formed by the flanges 19 is a divergent groove and the mating end of the studded member is complementally convergent, it will be seen that 40 a very tight joint is secured, and the resistance to angular movement of the side rails is correspondingly increased.

I claim:

A corner fastening for metal bedsteads comprising a pair of castings, one of said castings including a flat bearing face having a keyhole slot therethrough and outwardly tapering flanges at its opposite side edges, 50 the other casting having upper and lower flat bearing face portions, said portions connected centrally by an integral web extending rearwardly and upwardly, back of the upper bearing portion serving to brace said 55 portion, a stud or shank projecting forwardly from said web, a cammed head on said stud, said stud and head adapted to fit within the keyhole slot of the first named casting, the side edges of the stud carrying 60 casting reversely tapered to fit within the flanges of the first casting, and be drawn tightly thereto by cam action of the stud head.

WILLIAM A. KOCH.
